REFRIGERATOR LATCH

Lloyd L. Anderson, Grand Rapids, Mich., assignor to Winters & Crampton Corporation, Grandville, Mich., a corporation of Michigan

Application October 18, 1937, Serial No. 169,632

10 Claims. (Cl. 292—64)

This invention relates to latches adapted to be used in holding doors in a closed position. The latch of the present invention is of particular utility for use with refrigerators, though not limited to refrigerator use alone.

It is a primary object and purpose of the present invention to produce a very useful, practical and efficient latch at a low cost of manufacture and with a utilization of a minimum number of parts in the construction of the latch. A further object of the invention is to provide a latch in which the release thereof is accomplished through a very short movement of the holding means which maintains the latch in its operative latched position, thereby decreasing the size of the latch and the size of the supporting structure on which the movable latch bolt is mounted, resulting in greater economy of manufacture and simplicity in structure and operation.

20 The invention may be understood from the following description taken in connection with the accompanying drawings, in which:

Fig. 1 is a fragmentary horizontal section through the free edge portion of a refrigerator door and the adjacent door casing, showing the latch which is mounted on the door in plan view.

Fig. 2 is a vertical elevation and section substantially on the plane of line 2—2 of Fig. 1, looking in the direction indicated by the arrows.

30 Fig. 3 is a longitudinal section through the latch.

Fig. 4 is a similar section with the latch bolt in retracted position, and

Fig. 5 is a section taken substantially on the plane of line 5—5 of Fig. 3, looking in the direction indicated.

Like reference characters refer to like parts in the different views.

In the construction of the latch, a supporting housing of channel form is provided, having a web 1 and spaced apart sides 2, the free edge portions of which are turned outwardly at right angles, making flanges 2a through which screws or other suitable fastening devices are passed to secure the latch to the door. The latch bolt comprises a latching dog or head 3 to the opposite sides of which metal bars 4 are permanently secured adjacent one end and extend inwardly between the sides 2 of the support. Said bars 4 at 45 the end portions thereof farthest away from the head 3 are longitudinally slotted for a distance, as indicated at 5.

A pin 6 extends through the slots 5 on which, between the bars 4, a member is pivotally mounted comprising two spaced apart arms 7 connect-

ed by an integral cross member 8. The pivot pin 6 extends through the arm 7 at one end and near the opposite end a pin 9 extends through said arms 7 and also through the sides 2 of the support on which it is permanently mounted. 5 The latch bolt, pivot pin 6, the pin 9 and the structure comprised of the parts 7 and 8, in effect provide a toggle, the knuckle of which is at the pivot pin 6.

Between the head 3 and the pivot pin 6 a relatively heavy coiled compression spring 10 is located, the inner end thereof passing over the reduced end 11 of a spring locating member which is mounted on the pin 6, while the opposite end passes over a projection 12 which extends inwardly from the head 3 of the latch bolt. The latch bolt head 3 and the pins 4 attached thereto are thus permitted an inward longitudinal movement with respect to the pin 6, the extent of which is governed by the length of the slots 5. 20 Such movement is resisted by the coiled spring 10.

The latch bolt in its latched position is disposed against the web 1 of the support with the axes of the pins 6 and 9 disposed in a plane substantially parallel to said web 1, as in Figs. 1 and 25 3. The head 3 of the bolt is received in a U-shaped guide including a cross connecting portion 13 and spaced apart legs 14. Said legs lie inside the sides 2 of the support and permanently secured by spot welding or other equivalent connections. The latch bolt therefore may be retracted in two ways. One, by direct inward movement with a compression of the spring 10 and the other, by a pivotal movement of the arms 7 in a counterclockwise direction about the pin 9, 35 thereby breaking the toggle and moving to the position shown in Fig. 4.

In each of the sides 2 of the supporting member of the latch, slots 15 are cut each including an offset portion 16 connected with the longer 40 part of the slot by an inclined slot portion (see Fig. 3). The offset 16 of the slot is located nearest the pivot 6 and directly in front thereof. A pin 17 passes through said slots and extends between and through the sides 2 of the support and 45 is adapted to traverse the slots from the position shown in Figs. 1 and 3, to a position to the right thereof. At one of the edges of the slots the metal which is struck from the sides 2 of the support is pressed outwardly, making ledges 18, one for 50 each slot (see Fig. 1) to minimize the effects of wear on the pin 17 in its movements lengthwise of the slots.

Spaced apart links 19, connected by an integral cross member 20, are connected with the pins 6 55

and 17, the pins passing through opposite ends of said links. A coiled tension spring 21 of relatively light strength is located around the pin 9 and has one arm 22 thereof bearing against the 5 web 4 of the support and the other end 23 bearing against the pin 17, thereby tending to move said pin 17 to the left (Figs. 1 and 3) into the offsets 16 of said slots in the sides 2.

When the latch bolt is in its operative latching position, as shown in Figs. 1 and 3, the links 10 are disposed at right angles to a line connecting the axes of the pivots 6 and 9. The pin 17 bears against the outer sides of the offset portions 16 of the slots 15, providing a positive stop 15 against breaking of the toggle lever from the position in Fig. 3, to that shown in Fig. 4. But by moving the pin 17 along the shorter offset portions 16 of the slots, the stop against breaking the toggle is rendered ineffective, and the pin 17 20 traversing the inclined portion of the slot breaks the toggle toward the position shown in Fig. 4, thereby retracting the latching bolt head 3 as is evident.

As shown in Fig. 1, the latch having the structure described is mounted on and within a door, such as a refrigerator door, which door is hingedly mounted at one of its vertical edges on the refrigerator, the latch being mounted adjacent the opposite vertical edge so that the bolt head 30 3 may project beyond the edge of the door back of the outwardly extending lip 25 on the door which passes over the front side of the adjacent door casing 27 of the refrigerator; and on which a cushioning gasket 26 of rubber is secured which 35 is compressed when the door is closed and the bolt has engaged with the keeper 28 on the door frame, thereby providing a tight seal against the entrance of warm air and the escape of refrigeration. With the head 3 of the bolt engaged 40 with the keeper and with the parts of the latch in the position shown in Figs. 1 and 3, the door is held securely in closed position and cannot be opened until the pin 17 has been moved to the right in the slots 15. A slight movement only 45 of the pin 17 or until it has moved only sufficient to break the toggle outwardly and started it toward the position shown in Fig. 4 is required, whereupon the compressed cushioning members 26 exert their force against the outer side of the bolt head 3 to move it still farther from the 50 initial position shown in Fig. 3 to that shown in Fig. 4, whereupon the bolt is withdrawn from engagement with the keeper, the inner end of the plates 4 forming a part of the bolt following the path of an arc about the axis of the pivot 9.

The invention in this application is directed primarily to the latch structure which has been described. One means is shown for effectively moving said pin 17 to release the latch and thereby permit the door to be opened. It is, however, to be understood that such releasing means is one only of a large number of manually operable releasing means which may be used with the latch structure disclosed; and that the invention 65 is not in any sense to be restricted or limited to the particular latch bolt releasing means shown in the drawings and now about to be described.

As one form of bolt releasing means, two plates 29, preferably of the form shown, are pivotally mounted on a pin 30, the axis of which is substantially in alignment with the axes of the pins 6 and 17 when the bolt is in operative latching position (Fig. 3). Said plates are located at the inner sides of the sides 2 of the support and the pivot pin 30 therefore at its ends is mounted on

the said sides 2. The plates in effect are bell crank levers, the pivot 30 being at one end of one of the arms of said levers and the other arms of said levers lying against the pin 17, as in Fig. 3. A pin 31 connects the two plates 29 at the 5 elbows thereof a short distance to one side of the pivot 30. A yoke 32 is connected with the pin 31 at one end and at its opposite end to a push rod 33 which passes through the front side of the door 24 and into a space to receive it made in 10 a handle 34, attached to the door, which has a web 35 between its side edges reaching to the door and into which the pin 33 extends. A coiled spring 36 surrounds the pin within said web. A push bar 37 has flanges 38 at its inner edge, the narrower portion of the push bar extending through a slot in the handle 34. The outer end of the pin 33 comes against the inner side of the push bar 37. An inward movement of the push bar, caused by pressing against it with the hand of 15 the operator, compresses the spring 37, moves the pin 33 inwardly, turns the plates 29 in a clockwise direction about the pin 30, and thereupon moves the pin 17 to the right and out of the shorter offset portions 16 of the slots 15, breaking 20 the toggle of the latch structure, whereupon the door will be swung open and the latch bolt take the position shown in Fig. 4. When the latch bolt is released from its keeper and the door is opened, a release of the push bar 37 permits 25 the spring 36 to move it to its outer position and the spring 21 will cause the latch parts to swing back to the initial position shown in Fig. 3. On closing the door with the parts of the latch in such position, the inner cam side of the head 3 30 rides over the inclined cam side of the keeper 28, the bolt head 3 with the attached bars 4 moving bodily inward with a compression of the spring 10 until the nose of the head of the latch bolt 3 35 passes by the nose of the keeper, whereupon 40 spring 10 projects the latch bolt outwardly to have the head 3 thereof engage in the keeper recess, as in Fig. 1.

From the foregoing description the construction and operation of the latch which I have 45 produced is evident and may be clearly understood. The latch structure is made chiefly from sheet metal parts which are readily stamped and formed by dies. The assembly is simple and easy. The throw required to release the latch 50 bolt is reduced to a minimum, and the final retraction of the latch bolt is helped and in many cases provided solely by the force of compression of the gasket 26, which is compressed when the door is latched in closed position. The toggle structure of the latch and the abutment or stop means employed to prevent the toggle from 55 breaking so as to release the latch bolt from the keeper is simple, yet particularly practical, effective, and economical to build.

The invention is defined in the appended claims and is not to be limited other than may be necessitated by the terms of such claims.

I claim:

1. A latch structure comprising, a support having spaced apart connected sides, a latch bolt guide between said sides of the support and located at one end thereof, a member pivotally connected at one end to and lying between the sides of the support, said pivotal connection being 65 adjacent the opposite end of the support, a latch bolt pivotally connected to the inner end of said member and guided in said guide, said bolt and member normally lying in substantial alignment, a second member pivotally connected to 70

the same pivot which connects the first member and bolt and normally extending at right angles to the bolt and connected first member, the sides of said support having slots therein, a pin extending through the free end portion of said second member and seated at its ends in and adapted to traverse the slots, the material defining said slots furnishing an abutment against which the pin bears when the latch bolt and first member are in alinement with each other, thereby preventing movement of the latch bolt and connected member, and said slots being formed with angular portions adapted to be traversed by said pin whereby said latch bolt and first member may be moved, as specified.

2. A construction containing the elements in combination defined in claim 1, combined with a third member pivotally mounted on and between the sides of the support and adapted to engage with a side of the pin, the pivot of said third member being in substantial alinement with the pivotal connections of said latch bolt and said second member respectively, and means for manually turning said third member against the pin to move said pin in said slots and thereby free the latch bolt and connected member for movement.

3. A latch structure containing the elements in combination defined in claim 1, combined with a torsion spring surrounding the pivotal mounting of said first member, the ends of said spring bearing against said pin and against the support respectively, thereby tending to return the latch bolt and said members connected therewith to initial position.

4. A latch comprising, a support having spaced apart sides connected at one edge by a web, a latch bolt guide carried by and between the sides of the support adjacent one end thereof and spaced from the web whereby the web forms a part of said guide, a latch bolt comprising a bolt head and parallel bars connected one at each side of the latch bolt and extending inwardly therefrom between the sides of the support, the inner end portions of said bars being longitudinally slotted, a member comprising two spaced apart sides connected by a cross bar pivotally mounted at the outer ends of said sides on and between the sides of said support and adjacent the opposite end thereof, said sides extending to and between the bars of the latch bolt, a pin extending through the inner ends of the sides of said member and through the slots in said bars of the latch bolt, a coiled compression spring interposed between said pivot pin and the bolt head, a second member comprising two spaced apart sides connected by a cross bar pivotally connected to the ends of said pivot pin and normally extending at right angles to said web and to said latch bolt, a pin passing through the opposite ends of the sides of said second member, the sides of said support having slots through which the end portions of said pin pass, said slots containing two sections substantially parallel to the plane of the web connected by annular sections, the inner end portions of the slots being nearest to the web and located so that when said last mentioned pin is at the inner ends of the slots its axis and the axis of the first pin are located in a plane substantially perpendicular to the plane of said web.

5. A construction containing the elements in combination defined in claim 4, said sides of the

support at the edges of said slots farthest away from the web having outwardly extending bearing ledges for said second pin.

6. A construction containing the elements in combination defined in claim 4, combined with pivotally mounted manually operable means for engaging against said second pin and moving it in said slots, as and for the purposes specified.

7. A latch structure comprising, a support having spaced apart sides, a latch bolt guide between the sides of the support and located adjacent one end thereof, a member pivotally connected at one end adjacent the opposite end of the support and lying between the sides thereof, a latch bolt pivotally connected to the inner end of said member and guided in said guide, said bolt and member normally lying in substantial alinement, a second member pivotally connected at the pivotal juncture of the first member and bolt and normally extending substantially at right angles thereto, a pin extending through the free end portion of said second member, said sides of said support having slots therein through which the pin extends, and the material defining said slots providing an abutment against which the pin bears when the latch bolt and first member are in alinement with each other, thereby holding the bolt against movement.

8. A construction containing the elements in combination defined in claim 7, combined with pivotally mounted manually operable means for moving said pin in the slots to free the latch for movement.

9. A latch structure comprising, a support having spaced apart sides, a latch bolt guide secured to and between said sides of the support adjacent one end thereof, a member pivotally connected at one end to and between the sides of the support adjacent the opposite end of said support, a latch bolt pivotally connected to the inner end of said member and guided in said guide, a second member pivotally connected to said latch bolt and first member at the pivotal connection thereof and adapted to normally extend at right angles to said latch bolt and first member, interengaging means at the opposite end of the second member and the sides of said support for holding all of the members in a position against movement, and manually operable means for releasing said interengaging means whereby the latch bolt may be tilted and retracted in said guide.

10. A latch structure comprising, a support having spaced apart sides, a latch bolt guide carried between and at one end of the sides, a member pivotally connected at one end adjacent the opposite ends of said sides, a latch bolt pivotally connected to the inner end of said member and guided in said guide, said latch bolt and member normally being located in alinement and providing a toggle structure, a second member pivotally connected at one end to said latch bolt and first member at the pivotal connection thereof, interengaging means on said second member and the support for holding said second member in a position substantially at right angles to the length of said latch bolt and first member when the same are in alinement, and manually operable means for moving said second member to thereby release the latch bolt and permit it to tilt and move lengthwise in said guide, as specified.

LLOYD L. ANDERSON.
